UNITED STATES PATENT OFFICE.

HERMANN J. MOHLENHOFF, OF NEW YORK, N. Y., ASSIGNOR OF ONE-HALF
TO CHARLES D. NEWTON, OF NEW YORK, N. Y.

AUTOMATIC ENGINE-CONTROLLING DEVICE.

SPECIFICATION forming part of Letters Patent No. 740,454, dated October 6, 1903.

Application filed July 19, 1902. Serial No. 116,151. (No model.)

To all whom it may concern:

Be it known that I, HERMANN J. MOHLENHOFF, a citizen of the United States of America, and a resident of the city of New York, Bronx borough, county and State of New York, have invented certain new and useful Improvements in Automatic Engine-Controlling Devices, of which the following is a specification, reference being had to the accompanying drawings, forming a part thereof.

My invention relates to automatic engine-controlling devices, and particularly to automatically-controlled means for stopping a locomotive.

My invention consists in a motor carried by the locomotive and adapted when operated to stop the locomotive, as by closing the throttle-valve, and thereby cutting off the supply of steam to the engines thereof, tripping mechanism therefor carried by the locomotive, and certain improved means controlled from distant points for engaging and operating the tripping mechanism.

In carrying out my invention I provide a motor upon the locomotive and operatively connect same to the locomotive-throttle. I then provide tripping mechanism for starting the motor into operation, which tripping mechanism may be operated either by a system of track instruments under the control of preceding locomotives, each locomotive controlling the track instrument in the rear thereof, or by cams or the like, which may be set manually from a distance or employed in connection with a signaling system.

The object of my invention is to stop a locomotive by means outside of the direct control of the locomotive driver or engineer, so that same may be automatically stopped when entering a danger zone, when running past a signal, or, should it become necessary or desirable, by an operator at stations along the line.

I will now proceed to describe an apparatus embodying my invention and will then point out the novel features in claims.

In the drawings, Figure 1 is a general view, in side elevation, of an apparatus embodying my invention and showing the same applied to a locomotive, itself illustrated in dotted outline. Fig. 2 is a view in end elevation of the

same. Fig. 3 is a view in central longitudinal section, on a larger scale, of a motor employed. Figs. 4 and 5 are detail views of a tripping device. Fig. 6 is a diagrammatic view of a railroad-track and certain track instruments employed. Fig. 7 is a detail side elevation, on a larger scale, of one of the track instruments with the casing thereof in section. Fig. 8 is a top view thereof. Fig. 9 is a detail sectional view of a controlling-valve employed for the motor.

In the present embodiment of my invention the motor carried by the locomotive is designated in the drawings as a whole by the reference character 1, the piston-rod or any other operating member of which engages the throttle-valve 2. The motor herein comprises a cylinder 3 and a piston 4, having a piston-rod 5. The piston-rod 5 is connected with a lever 6, suitably fulcrumed at 7, and the opposite end of the said lever has a pin 8, which is received within a slot 9 of the stem of the throttle-valve. The throttle-valve owing to this slotted connection is free to be operated by its lever 10 in the usual manner when the motor is in its rest position, which is the position in which it is shown in the drawings, because the stem of the throttle-valve is at such times free of the lever 6. The motor is provided with an exhaust-valve 11, whose normal position is closed and in which position it is shown in the drawings. An operating-piston 12 is located in the cylinder 13 and connects a piston-rod 14 with a lever 15 for operating the said exhaust-valve. When the piston moves forwardly, or from right to left, as shown in Fig. 3 in the drawings, air confined within the cylinder 3 in advance of the piston is forced through a connection 16 to the cylinder 13 in advance of the exhaust-valve-operating piston 12. The air being partially compressed will force the operating-piston 12 rearwardly in its cylinder to open the exhaust-valve. Air-ports 17 and 18 in cylinder 13 permit air in the rear of the piston 12 to be expelled from the cylinder 13 during the rearward movement of its piston 12, and in the final movement of the said piston the port 17, having been overridden by the piston 12, will be opened in advance of the said piston and the excess of compressed

air between the two pistons 12 and 4 will be discharged therethrough.

A controlling-valve 19 is provided for the motor and is located in a pipe 20, connected 5 with a source of fluid-pressure supply and preferably with the steam-space of the locomotive-boiler. The controlling-valve, which is shown in detail in Fig. 9, is preferably a two-way valve, which when in one position 10 opens the interior of the cylinder 3 behind the piston 4 to exhaust or atmosphere and when in the other position connects the cylinder with motive fluid under pressure. By this arrangement should any leakage occur 15 in the valve the motive fluid will merely discharge to exhaust or atmosphere and will not tend to operate the motor 1, nor will water of condensation tend to collect in the rear end of the cylinder or in the portion of the pipe 20 between it and the valve 19. I have provided automatic means controlled from a distance for moving the valve 19 and hence for operating the motor 1 to stop the engine when desired. I have provided a block system of 25 track instruments operated by the locomotives themselves in their movements along the line to set and release cams for operating a trip upon the succeeding locomotive should such locomotive attempt to approach too near 30 its preceding locomotive, and I have also provided other cams which may be operated from a distance by hand or in connection with a signal system by which a locomotive may be stopped when desired opposite any predetermined point. The block system, which is 35 shown diagrammatically in Fig. 6, and the track instruments, which are shown on a larger scale in Figs. 7 and 8, comprise track-instrument levers 21 and 22. The lever 21 is 40 pivoted to or in proximity to the track, as at 23, and the lever 22 is pivoted by slotted connection to a pin 24. The lever 21 has secured thereto an arm 25, the end of which has an 45 uprising cam portion 26, adapted to be raised into or lowered out of the path of movement of a tripping device carried by the locomotive. Each pair of track-instrument levers 21 and 22 are connected to another pair of track-instrument levers 27 and 28, arranged 50 in proximity to the track at some distance farther along same. The track-instrument levers 21 and 22 are connected by a link 29 to a bell-crank lever 30, and the levers 27 and 28 are connected by a similar link 31 to a similar bell-crank lever 32. A connecting-rod 33 connects the bell-crank levers 30 and 32 together. The parts are constructed and arranged so that when the track-instrument levers 21 and 22 have been depressed by a 55 passing locomotive track-instrument levers 27 and 28 are in a condition to be depressed by the locomotive in its further movement along the track, and the depression of the track-instrument levers 27 and 28 will in turn 60 reset or raise the track-levers 21 and 22 in position to be operated or depressed by the next succeeding locomotive.

The tripping device carried by the locomotive and which is arranged to be in the path of the cams 26 when in their operative positions comprises a finger 34, having a double fulcrum 35 36, a connecting-rod 37, pivotally connected to the finger 34 at 38, and a spring 39, normally tending to hold the finger 34 in an intermediate position between its two 70 fulcra. The connecting-rod 37 is connected to one arm of a bell-crank lever 40, the other arm of which is connected to a connecting-rod 41, whose opposite end connects with one arm of another bell-crank lever 42, the other 75 arm of which is connected through a slotted link 43 with an operating-lever 44, secured to the valve 19. Should a locomotive in its movement along the track pass a track instrument which has been operated or depressed to bring its cam 26 in the path of movement of its tripping-finger 34, the tripping-finger 34 carried thereby will be rocked upon one or other of its fulcra, in accordance with in which direction the locomotive is running, against the resistance of the spring 39, and movement will be transmitted through the connecting-rod 37, bell-crank lever 40, connecting-rod 41, bell-crank lever 42, link 43, and operating-lever 44 to the controlling- 85 valve 19. The controlling-valve 19 thus operated will connect the rear of the cylinder 3 with the source of fluid-pressure supply, and the motor will be operated to close the throttle-valve of the locomotive in a manner 90 before explained. Directly the tripping-finger has passed the cam 26 the tripping-finger 34, the connecting-rods 37 and 41, and the bell-crank levers 40 and 42 will be returned to their normal positions by means of the 95 spring 39. The controlling-valve 19 and its operating-lever 44 are not affected, however, by the return movement of the above-mentioned parts because of the slotted connection between the link 43 and the lever 44. 100

The operating-lever 44 is provided with a handle, as is also the exhaust-valve lever 15, so that the valves may be returned to their normal positions manually by the locomotive operator after they have been automatically 115 thrown to stop the locomotive.

The system of track-levers hereinbefore explained may be located in blocks along the track in a manner readily understood, and I preferably overlap the blocks, as shown in 120 Fig. 6, so that the track instrument of a block which a locomotive is entering will be set at "danger" behind the locomotive before the track instrument at the entrance of the block which the locomotive is leaving is set at 125 "safety." It will be apparent that a locomotive in entering a block sets the track instrument in danger position behind it—that is to say, the track-levers are set in such a position as to raise their cam 26 to operate the 130 tripping device of a locomotive following too closely behind. It will also be apparent that in leaving the block and in operating the track-levers at the end thereof the track in-

strument at the entrance of such block will again be set to "safety," so that another locomotive and train may be permitted to enter the block controlled thereby.

5 I have shown in Fig. 7 a spring 45, which may be employed to maintain the track-levers in their depressed or raised positions, in accordance with which position they may beset. I preferably also provide the locomotive with 10 a tripping device 46, similar to the before-mentioned tripping mechanism, and which for convenience may be arranged upon the roof of the cab of the locomotive and connected to the operating-lever 44, as shown in Fig. 1. I 15 then provide cams or trippers 47 at predetermined points along the line, as shown in Fig. 2, which cams or trippers may be employed in connection with a signaling system, automatic or otherwise, or which may be set by 20 hand from a distant point by suitable connections in a manner well understood to those skilled in the art to which this invention appertains. By this means I may provide a number of points along a tunnel, for instance, 25 at which the locomotive may be stopped when desired regardless of the block system of track instruments or entirely independent thereof.

What I claim is—

30 1. In an automatic engine-controlling device, the combination with a motor adapted to engage an engine throttle-valve, and a valve for controlling supply of motive fluid to the motor, of tripping mechanism, carried by the 35 engine, for operating the motor-controlling valve, said tripping mechanism comprising a lever having two fulcra, upon either of which it is adapted to be rocked in accordance with in which direction pressure is applied there- 40 to, a pull-rod connected to said lever between the two said fulcra, and a spring for holding the lever in its normal position, and a track instrument for engaging the tripping mechanism.

45 2. In an automatic engine-controlling device, the combination with a main cylinder, a piston therein, said piston adapted to engage an engine throttle-valve, an auxiliary cylinder in open communication at one end 50 with the forward end of the main cylinder, said main cylinder having an exhaust-passage at its rear end, a valve in said exhaust-passage, a piston in said auxiliary cylinder, and a connection between said exhaust-valve 55 and said auxiliary piston, of a valve for controlling supply of motive fluid to the rear end of said main cylinder, and means, discon-

nected from the engine or any part movable therewith, for operating the motor-controlling valve.

60

3. In an automatic engine-controlling device, the combination with a main cylinder, a piston therein, said piston adapted to engage an engine throttle-valve, an auxiliary cylinder in open communication at its forward end with the forward end of the main cylinder, and at its rearward end with exhaust, an exhaust-passage at its rear end, a valve in said exhaust-passage, a piston in said auxiliary cylinder, and a connection between said exhaust-valve and said auxiliary piston, of a valve for controlling supply of motive fluid to the rear end of said main cylinder, and means, disconnected from the engine or any part movable therewith, for operating the motor-controlling valve.

65

4. In an automatic engine-controlling device, the combination with a main cylinder, a piston therein, said piston adapted to engage an engine throttle-valve, an auxiliary cylinder in open communication at its forward end with the forward end of the main cylinder, and at its rearward end with exhaust, said auxiliary cylinder having also an exhaust-port adapted to be overridden by the 80 piston in its rearward movement, an exhaust-passage at its rear end, a valve in said exhaust-passage, a piston in said auxiliary cylinder, and a connection between said exhaust-valve and said auxiliary piston, of a 85 valve for controlling supply of motive fluid to the rear end of said main cylinder, and means, disconnected from the engine or any part movable therewith, for operating the 90 motor-controlling valve.

95

5. In an automatic engine-controlling device, the combination with a motor adapted, when operated, to stop the engine, and tripping mechanism therefor, of a track instrument, for engaging said tripping mechanism, comprising two sets of track-levers arranged at opposite ends of a predetermined section of track, a connecting-rod connecting the said levers together, whereby one set of levers is always in the opposite position to the other, and a spring operating to exert tension in opposite directions with respect to said connecting-rod, according to the relative positions of the track-levers to maintain the said levers in either position they are set.

HERMANN J. MOHLENHOFF.

Correction in Letters Patent No. 740,454.

It is hereby certified that Letters Patent No. 740,454, granted October 6, 1903, upon the application of Hermann J. Mohlenhoff, of New York, N. Y., for an improvement in "Automatic Engine-Controlling Devices," was erroneously issued to Hermann J. Mohlenhoff and Charles D. Newton, as joint owners of said invention; whereas the patent should have been granted to said *Charles D. Newton*, he being sole owner of the entire interest as shown by the assignments of record in the Patent Office; and that said Letters Patent should be read with these corrections therein that the same may conform to the record of the case in the Patent Office.

Signed and sealed this 27th day of October, A. D., 1903.

[SEAL.]

F. I. ALLEN,
Commissioner of Patents.
